UNITED STATES PATENT OFFICE.

BYRON PHELPS, OF SEATTLE, WASHINGTON.

TOILET-PAPER HOLDER.

1,292,640.

Specification of Letters Patent. Patented Jan. 28, 1919.

Application filed March 27, 1918. Serial No. 224,930.

To all whom it may concern:

Be it known that I, BYRON PHELPS, a citizen of the United States, and resident of the city of Seattle, county of King, and State 5 of Washington, have invented certain new and useful Improvements in Toilet-Paper Holders, of which the following is a specification.

My invention relates to roll paper holders 10 and particularly to holders intended for use in holding rolls of toilet paper.

The object of my invention is to produce a device for this purpose which shall be cheap in first cost, simple and easy, both to 15 install and to place the paper in place, so that any person may put this up and keep it supplied.

My invention comprises the novel features which will hereinafter be described and then 20 particularly pointed out in the claims.

The accompanying drawings show my invention embodied in its preferred form of construction.

Figure 1 shows the device in its preferred 25 type of construction, in perspective, a roll of paper being shown in position.

Figs. 2 and 3 are perspectives of modified construction using different types of base member.

30 My device has two parts, an arm and a base to which the arm is pivoted. The arm is preferably made of a bar of round iron or heavy wire. This bar is bent so as to form two parallel sections, 1 and 4. These 35 two sections are separated in position and are connected by the central portions of the rod, which central portion is preferably bent so as to form a section 2 next to the section 1 which is at right angles thereto and of a 40 length to extend to the outer edge of the roll of paper when it is in place upon the section 1. The inner end of the section 2 is joined to the pivot section 4 by section 3, which preferably, although not necessarily, occupies 45 an inclined position, as shown.

The pivot section 4 is considerably shorter than the section 1, which is substantially the length of the roll of paper 7. The base to which the arm is pivoted is, in the preferred 50 construction, considerably narrower than the length of the roll 9 and of such material thickness that when the roll swings down into contact with the base it is supported somewhat away from the wall and with the

ends of the roll projecting well beyond the 55 side edge of the base 6. In consequence, the depending end of the paper is held away from the wall enough to make it easy to get the fingers behind it and get hold of it.

The type of pivot base shown in Fig. 2, 60 which shows a metal plate 7 having an eye for the pivot section 4, may be used, but this does not secure the above results and is therefore not so much preferred.

In Fig. 3 is shown a pivot base 8, which 65 in outline closely resembles that of Fig. 1, but is made of stamped sheet metal, or other suitable molded or stamped sheet material.

The free or swinging end of the rod has a tip section 5 which is bent back toward 70 the pivot and prevents endwise movement of the roll. This is short enough to pass freely through the hole in the roll. The pivot base is provided with holes for the reception of securing screws or nails, as 60 and 70.

75 It is desired to call attention to the fact that when the paper is drawn out the inner wall of the tubular core upon which the roll is wound, has to slide over the bar section 1, thereby producing a friction which prevents 80 excessive overturning of the roll.

This device may be put up by any one, as it only necessitates placing of a couple screws or nails. Also, any one would understand how to place a new roll thereon. It 85 is exceedingly simple and cheap in design and of such character that any one may take care of the same and keep it supplied with paper.

90 What I claim as my invention is:

1. A roll paper holder comprising a metal rod having two parallel and separated sections, one of these being at one end of the rod and serving as a pivot axis and the other being slightly removed from the other 95 end of the rod and serving to receive the paper roll, the extremity of this end of the bar being bent back toward the pivot section and said pivot and roll-holding sections being connected by the central portion of the 100 rod by a section which is at right angles to and joins with one end of the roll receiving section and other connecting this right angled section with the pivot section and extending in an inclined direction, and 105 a base upon which the pivot section is journaled.

2. A roll paper holder comprising a base

member of a width considerably less than the width of the paper it is designed to hold, a bar pivoted by one end upon this base and having its other end substantially parallel with and separated from the pivot section and of a length to extend through the paper roll, the free end of this section having a

laterally bent tip to prevent accidental displacement of the roll, and the section being positioned to extend at each end beyond the 10 side edges of the base.

Signed at Seattle, Washington, this 20th day of March, 1918.

BYRON PHELPS.
